UNITED STATES PATENT OFFICE.

ULRIK SEVERIN SJÖSTRAND, OF SUNDBYBERG, SWEDEN.

DEVICE FOR SEARCHING SUBMARINE MINES, &c.

No. 818,479.

Specification of Letters Patent.

Patented April 24, 1906.

Application filed September 28, 1905. Serial No. 280,457.

To all whom it may concern:

Be it known that I, ULRIK SEVERIN SJÖSTRAND, a subject of the King of Sweden and Norway, and a resident of Sundbyberg, Sweden, have invented a new and useful Improvement in Devices for Searching Submarine Mines and the Like, of which the following is a specification, reference being had to the drawings accompanying and forming a part hereof.

This invention relates to an improved device for searching submarine mines and the like.

The object of the invention is to provide a device of the said kind which will be simple in construction and reliable in function.

The invention consists, chiefly, in the combination of buoys, steering means on said buoys adapted to keep the same at a distance from each other during the motion through the water, water-kites suspended from the said buoys, and one or more catch-cords or the like between the said kites adapted to strike the mines or the like. The buoys are by means of tow-lines connected to a boat or vessel, and the said tow-lines may be connected to a winding device or the like placed in the boat or vessel and suitably provided with an automatically-working stopping device of any suitable construction adapted to release the winding mechanism when the stretching in the tow-lines after the cord or cords connecting together the kites is suddenly increased, so that the tow-lines can be wound off until the vessel can be stopped.

In the accompanying drawings I have shown an embodiment of my invention.

Figure 1 shows a perspective view of my improved device, and Fig. 2 shows a top view of the same.

Referring to the drawings, a winding device 2 is placed in the stern of the vessel 1, and to the same are connected two tow-lines 3, each attached to one of the buoys 4. The latter are provided with keels 5 or other steering devices, on account whereof the buoys tend to move away from each other. In using keels such movement may most suitably be effected by connecting the tow-lines, by means of rings 6 or the like, for instance, to three cords or the like, of which one, 7, is attached at or near the lower edge of keel 5, while the two others, 8 and 9, are each attached at or near one of the ends of the keel, the length of the said cords being so chosen that the attaching-point of the tow-line is at the

side of the keel and somewhat in front of its middle, so that the keel while moving through the water will place itself obliquely in relation to the direction of movement. Since 60 the attaching-points of the tow-lines are located on the sides of keels facing each other, the buoys will obviously tend to move away from each other when being drawn through the water. From the keels 5 of the buoys 65 are, by means of cords 10 or the like, suspended water-kites 11 of any well-known or suitable construction, which are capable of keeping themselves at a constant depth independently of the speed at which they move through 70 the water. Somewhat above the kites are provided edgewise-arranged plates 12, which are pivotally attached to the cords 10 and are connected to each other by means of one or more cords 13 or the like adapted to strike 75 eventual mines. Since the ends of the cord or cords 13 are attached to the said plates 12 at some distance from the axis of rotation of the plates 12, the latter will place themselves obliquely in relation to the direction of move- 80 ment, and therefore tend to move away from each other, thereby keeping the cord or cords 13 stretched. Though the provision of the said plates 12 is quite important in the present invention, inasmuch as the kites, which 85 offer little resistance against laterally-working strains, will be fully freed from such strains, said plates are not necessary.

The device described above works as follows: When the buoys and their kites have 90 been dropped down from the vessel and the tow-lines wound off to the desired length, buoys and kites will place themselves approximately in the manner shown in the drawings, whereby the catching-cord 13 will be stretched 95 in a certain degree and move at a constant depth, at which it will be kept by the kites. When the catching-cord 13 strikes a submarine mine or the like, the stress in the tow-lines will be increased very essentially, and such increase of the stress may be used 100 to release a stopping device of any suitable construction, stopping the winding mechanism in order to prevent bursting of the tow-lines or the catching-cord. Simultaneously 105 with the release of the stopping device a signaling device may be put in operation.

Though in the drawings are shown only two buoys and two kites, it is evident that the number of buoys and kites may be chosen 110 at will. Eventually the buoys and the kites may be arranged in groups after each other,

in which case the cords connecting together the kites may be arranged to move at different levels in the several groups.

The kind of water-kites which I prefer to use in carrying out the present invention is that described in my United States Patent No. 717,129, dated December 30, 1902, because I do not know of any other kind of kites that are capable of moving at constant depths.

Having now described my invention, what I claim as new, and desire to secure by Letters Patent, is—

1. In a device for searching submarine mines and the like the combination of buoys, steering means on said buoys adapted to keep the same at a distance from each other during the motion through the water, water-kites suspended from the said buoys, and a

catch-cord between the said kites, substantially as and for the purpose set forth. 28

2. In a device for searching submarine mines and the like the combination, of buoys, steering means on said buoys adapted to keep the same at a distance from each other during the motion through the water, water-kites, suspension - cords between the said buoys and kites, swingable plates on said suspension-cords, and a catch-cord between the said swingable plates, substantially as and 25 30 for the purpose set forth.

In testimony whereof I have signed my name to this specification in the presence of two subscribing witnesses.

ULRIK SEVERIN SJÖSTRAND.
